VENDING MACHINE

Addison P. McKelvy, Kansas City, Mo., assignor
to Alfred D. McKelvy, New York, N. Y.

Application February 14, 1938, Serial No. 190,464

7 Claims. (Cl. 312—80)

This invention relates to vending machines and contemplates such a structure that is adapted to vend articles one at a time from receptacles wherein is packed a large number of said articles, and one of the primary objects of the invention is the contemplation of unique structure for transferring the vendible articles from the receptacle to the discharge opening of the machine in such manner that the delivery is rendered efficient and relatively free from objectionable circumstances such as clogging and the like.

One of the important aims of this invention is to provide a vending machine for cigarettes, said machine having unique parts for removing the cigarettes from the original package bearing the internal revenue stamp and delivering the cigarettes singly from the machine.

Another important object of this invention is to provide a vending machine for dispensing cigarettes from the original package or packages one at a time, said machine including a novel hopper and agitator construction which is preferably disposed intermediate two of the original packages of cigarettes for the purpose of receiving cigarettes therefrom and delivering the same singly to a point where an operator of the machine will receive the same.

Some of the most important objects of the invention relate to the specific structural features and their combinations and will be made clear during the course of the specification, referring to the accompanying drawings, wherein:

Figure 1 is a top plan view of a vending machine embodying this invention.

Fig. 2 is a side elevation of the same.

Fig. 3 is a vertical, longitudinal section through the vending machine, taken on line III—III of Fig. 1.

Fig. 4 is a longitudinal, horizontal section through the machine, taken on line IV—IV of Fig. 3, with the ejecting plate shown in dotted lines in the opposite extreme position, and,

Fig. 5 is a detailed, perspective view of one of the agitator plates, showing the same entirely removed from the machine.

Fig. 6 is a fragmentary sectional view taken on line VI—VI of Fig. 4.

In practice it is customary to pack cigarettes in relatively flat receptacles, within which has been placed a lining or apron. In the trade these packages are known as "Flat Fifties" or some such similar term and the cigarettes are arranged in two, double-layer rows with the ends 55 of the cigarettes in one of said rows abutting

the ends of the cigarettes in the other row. Longitudinal displacement of the cigarettes does not occur to any great extent and the hereinafter described mechanism is designed to alternately feed cigarettes from the aforesaid two rows thereof; that is to say, a cigarette emanating from one of the rows is discharged, then a cigarette from the other row, and so on. These receptacles are closed and sealed with an internal revenue stamp which must be broken before the contents of the receptacle can be removed, and in machines of this character where cigarettes are vended singly from such a package, it is necessary to utilize the box or original package as the receptacle for holding the supply of cigarettes in the machine. After one box has been emptied, another is placed so that the operation of the machine might continue.

The vending machine contemplated by this invention includes parts for accommodating two boxes of cigarettes, each having fifty units therein, said boxes being disposed on the same horizontal plane and in spaced-apart relation with a hopper and ejecting structure therebetween and below so that one hundred cigarettes might be passed through the machine before reloading becomes necessary. In practice, the vending machine might incorporate novel coin mechanism and must, of necessity, include a case having suitable openings through which may be viewed the cigarettes being vended. Parts embodying this invention are illustrated in the accompanying drawings and like reference characters are used to designate similar elements of the structure.

A base 8 carries two spaced-apart sides 10, between which are supported frames 12 that carry receptacles 14 and, as shown in Fig. 3, these frames should be created in such a manner that receptacle 14 is engaged in a way to preclude displacement in any direction.

Each receptacle 14 carries a number of cigarettes 16 and, as is the practice, these cigarettes 16 are packed in two rows with the cigarettes arranged in end-to-end relation. Thus receptacle 14 is twice the length of one cigarette 16 and so hopper 18, interposed between frames 12, must likewise be of a length sufficient to receive two cigarettes 16 in end-to-end relation. In this instance, however, hopper 18 is appreciably longer 50 so that in the event cigarettes being fed from each side should overlap, there will be no clogging and complete freedom of passage is presented.

Apron 20 is utilized to feed cigarettes 16 from 55

receptacle 14 into hopper 18 and the means for so feeding the cigarettes includes a transverse shaft 22 journalled in sides 10 and geared to operating lever 24 through gear 26, pinion 28, 5 gears 30 and 32 and thence across to intermeshing gears 34 by way of shaft 36 and pinion 38. Grasping handle 40 and pulling operating lever 24 against the action of spring 42 will cause gears 34 to rotate through a fraction of a turn, 10 thereby turning shafts 22 which grip one end of apron 20. Apron 20 may be releasably affixed to shaft 22 by a grip bar 44 which is within longitudinal groove 46 formed in shaft 22 and which is pivotally affixed for swinging movement to and 15 from said position as at 48. Heads 50 are in screwthreaded engagement with one end of shaft 22 to frictionally grip the respective gear 34 and when it is desired to unwind apron 20 from shaft 22 during the step of replacing receptacle 14, it is 20 but necessary to loosen head 50, grasp the free end of apron and pull the same free from its engagement about shaft 22.

During the operation of the machine, and while one end is in engagement with shaft 22, the other 25 end of apron 20 is held against movement by clamp 52 which is disposed above and in spaced relation to shaft 22 so that a straight line joining the two (shaft 22 and clamp 52) will be on an incline tending to roll the cigarettes into hopper 30 18 over the edge of the side of receptacle 14 and through its open top, as shown in Fig. 3.

It is the intention of this invention to releasably secure upon 20 at clamp 52, and to do this, there is provided a yieldable, resilient member 54 pivotally affixed to rigid member of clamp 35 52 as at 56 and held in clamping engagement by catch 58 which is nothing more than the ordinary pin and notch construction 60 and 62 respectively. Resilient member 54 is slightly 40 arcuate when it is not engaged by the catch, and since shaft 22 exerts a pull through apron 20 upon member 54 in the proper direction to disengage the catch 58, it is obvious that as the machine is operated and as apron 20 is wound 45 upon shaft 22, the apron will be drawn free from the clamp when all of the cigarettes have been discharged from one of receptacles 14. Thus the machine is not locked against movement when the same has been emptied.

50 A unique hopper 18 is supported by sides 10 and a platform 64, and is formed to present two overlapping, offset, interconnected compartments 66, as shown in Fig. 4, each of which is appreciably longer than cigarette 16. Hopper 18 has a flared portion at the upper part thereof 55 to form a mouth into which are fed cigarettes 16 from each side. Obviously, as the cigarettes become offset or out of alignment in a longitudinal direction they will pass down through hopper 18 without trouble.

60 To further insure positive feeding, there is provided an especially formed agitator in the nature of a rebent plate 68. The bight of this plate rests upon the edge of hopper 18 and wall 70 of plate 68 projects into hopper 18 at the mouth, while wall 72 extends below the flared upper portion of hopper 18.

65 A series of openings 74 is formed through the wall of hopper 18 and wall 70 of plate 68 is provided with a number of arcuate fingers 76, one of which projects through each of said openings 74. Thus when plate 68 is rocked about its line of connection at its bight, fingers 76 will preclude cigarettes from passing back beneath wall 70 and when wall 70 is lifted to a position shown

in Fig. 3, the entire bulk of cigarettes being fed will be affected by a movement of a portion thereof at the mouth of opening 18. As shown in Fig. 1, there are two plates 68 positioned to act upon the two columns of cigarettes formed 5 in hopper 18.

In ejecting cigarettes 16 from hopper 18 singly or one at a time, reciprocating plate 78 comes 10 into play. This plate 78 has a pair of overlapping, spaced-apart slots 80 formed therethrough which underlie hopper 18 and one of which is always in register to receive a cigarette therefrom. As one slot 80 is receiving a cigarette 16 from hopper 18, the other slot 80 is in register with one of the discharge openings 82 formed 15 through platform 64 so that a cigarette 16 will be fed on to apron 84 where it is available to the operator. It will be noted that the openings 82 in the platform are disposed in offset relation in order that they will respectively register with the openings in the ejecting plate. Plate 78 is rectilinearly reciprocable by movement of lever 24 and each movement is imparted to plate 78 through eccentric shaft 86, upon one end of which is mounted pinion 28 and 25 gear 30. The eccentric, offset portion 88 of shaft 86 should be centrally disposed and a link 90 connects portion 88 with plate 78, as shown in Fig. 3. Manifestly, when lever 24 is operated, the parts previously described will be actuated to 30 feed cigarettes into hopper 18 and simultaneously plate 78 will be moved in one direction.

35 Guide slot 92 formed in member 94 insures the proper amount of movement by engagement with lever 24 and spring 42 retrieves lever 24 when it is released. Obviously, a ratchet and dog construction 96, of well known type, must be used to permit lever 24 to return without affecting the other parts of the mechanism. To simultaneously operate agitator plate 68, there is provided 40 similar standards 98 which engage wall 72 of each plate 68 alternately when plate 78 is reciprocated. Standards 98 are carried by plate 78 and their upper ends strike wall 72 to lift walls 70 that are projected into hopper 18. The 45 action of gravity and the weight of cigarettes resting upon wall 70 will cause plate 68 to return to a normal position where wall 70 lies directly upon the flared portion of hopper 18.

The operation of this machine and the relation 50 of parts forming the same is clear in the foregoing specification, and while the preferred form of the invention has been illustrated and described, it is desired to be limited in the enjoyment of the invention only by the spirit thereof and 55 the scope of the appended claims.

Having thus described the invention, what is claimed as new and desired to be secured by Letters Patent is:

1. In a vending machine of the character 60 described, a hopper having a flared top portion forming its mouth, said flared portion having openings formed through the wall thereof; means to feed vendible units into said hopper through the mouth; means at the bottom of said hopper 65 for singly ejecting the units therefrom; an agitator at the mouth of said hopper comprising a rebent plate, V-shaped in cross section, hanging upon the upper edge of the hopper along its bight, one wall of said agitator projecting 70 into the flared portion of the hopper and having fingers thereon projecting through said openings and toward the other wall whereby to bridge the space therebetween; and means carried by 75 said ejecting means and adapted to be moved to 80

engage the other wall of said agitator to move the same around its line of bearing.

2. In a vending machine of the character described, a hopper having a flared top portion forming its mouth and having openings formed through the flared portion thereof; movable means to feed vendible units into said hopper through the mouth; means at the bottom of said hopper for singly ejecting the units from the hopper; an agitator at the mouth of said hopper; and means associated with said ejector means and operable thereby for actuating the agitator, said agitator comprising a rebent plate hung upon the upper edge of said hopper with the bight in engagement with the hopper edge, one wall of said plate projecting into the mouth of the hopper and having fingers projecting toward the other wall and through the openings formed in the hopper wall.
3. In a vending machine of the character described, a hopper having a flared top portion forming its mouth and having openings formed through the flared portion thereof intermediate its edges; movable means to feed vendible units into said hopper through the mouth; means at the bottom of said hopper for singly ejecting the units from the hopper; an agitator at the mouth of said hopper; and means for actuating the agitator, said agitator comprising a rebent plate hung upon the upper edge of said hopper with the bight in engagement with the hopper edge, one wall of said plate projecting into the mouth of the hopper and having fingers projecting toward the other wall and through the openings formed in the hopper wall, said means for actuating the agitator including a standard carried by the movable ejecting means, one wall of said rebent plate projecting into the path of travel of said standard.

4. A vending machine of the kind specified comprising a pair of vendible commodity receptacles disposed in spaced apart relation wherein the vendible commodities are arranged in rows at each end thereof; a hopper interposed between said receptacles; means for feeding the commodity from the receptacles into said hopper; a platform below said hopper having offset discharge openings formed therethrough; and a reciprocating ejecting plate positioned below said hopper and above said platform, having a pair of offset, overlapped slots formed therein to receive vendible commodity units from opposite ends of the hopper and to register with said discharge openings in the platform as the plate is reciprocated, whereby a unit emanating from first one row and then from the other is ejected from the vending machine.

5. A vending machine of the kind specified comprising a pair of vendible commodity recep-

tacles disposed in spaced-apart relation; a hopper interposed between said receptacles; means for feeding the commodity from the receptacles into said hopper; and a reciprocating ejecting plate below said hopper, said hopper formed to present a pair of offset, overlapping connected compartments, said reciprocating ejecting plate having a pair of offset, overlapped, spaced-apart slots formed therein, movable to and from positions in register with the compartments of said hopper whereby to alternately receive units of the vendible commodity therefrom, and a platform positioned below said ejecting plate and having openings formed therethrough to receive and discharge said units.

6. A cigarette vending machine adapted to singly eject cigarettes from the original package wherein the cigarettes are arranged in two rows having the cigarettes in each row positioned in side-by-side relation and the ends of the cigarettes in one row abutting the ends of the cigarettes in the other row, comprising a hopper formed with two transversely offset compartments to receive cigarettes from both rows simultaneously and to maintain the cigarettes emanating from one row segregated from those emanating from the other row; and an ejecting assembly positioned below said hopper and including a movable plate having formed therein transversely offset openings adapted to simultaneously register with said hopper compartments and including a stationary platform positioned below said movable plate and having transversely offset openings therein to register with said movable plate openings whereby to alternately receive and discharge from said hopper, cigarettes emanating from first one row of the original package, then the other.

7. A cigarette vending machine adapted to singly eject cigarettes from the original package wherein the cigarettes are arranged in two rows having the cigarettes of each row positioned in side-by-side relation and the ends of the cigarettes in one row abutting the ends of the cigarettes in the other row, comprising a hopper having transversely offset portions formed to receive cigarettes from both rows simultaneously and to maintain the cigarettes emanating from one row segregated and in longitudinal offset relation with the cigarettes emanating from the other row; a platform positioned below said hopper having transversely offset discharge openings formed therethrough; and means including a member having transversely offset cigarette receiving openings manually movable to eject a cigarette emanating first from one portion of the hopper, then the other, through said discharge openings.

ADDISON P. McKELVY. 60
